C. C. CADY, OF WEST UNION, IOWA.

Letters Patent No. 61,047, dated January 8, 1867.

IMPROVEMENT IN CAR-COUPLING.

The Schedule referred to in these Letters Patent and making part of the same.

TO ALL WHOM IT MAY CONCERN:

Be it known that I, C. C. CADY, of West Union, in the county of Fayette, and State of Iowa, have invented a new and improved Car-Coupling; and I do hereby declare that the following is a full, clear, and exact description thereof, which will enable others skilled in the art to make and use the same, reference being had to the accompanying drawings, forming part of this specification, in which—

Figures 1 and 2 are side sectional views of my invention, taken in the line $z z$, fig. 3.

Figure 3, a plan or top view of the same.

Similar letters of reference indicate like parts.

This invention relates to a new and improved car-coupling, of that class which are self-coupling, and it consists in having a fixed-hook in each draw-head, for the link or shackle to catch over, in connection with a link-raiser, spring, and lever, applied to each draw-head, all arranged as hereinafter fully shown and described.

A A represent two draw-heads, which are secured to their respective cars in the usual or any proper manner. The front ends of the draw-heads are of the ordinary flaring form, and at the bottom of the front part of each draw-head there is a fixed hook, B, for the link or shackle C to catch over. In each draw-head there is what I term a link-raiser, D, composed of two arms, $a b$, the lower arm, a , being forked or divaricated, and embracing the hook B in its draw-head, that is to say, a prong being at each side of said hook. The upper arm b is connected by a chain, e, with a lever, E, on the outer end of the platform of the car just over the draw-head. The rear ends of these link-raisers D are connected by a joint, d, with the bottom of the draw-head, and on said rear parts, just in front of the joints d, a spring, F, presses, said springs being attached to the bottom plates of the draw-heads. From the above description, it will be seen that when the link C is inserted in one draw-head, and its inner end in the angle of the raiser D, the link will be retained in nearly a horizontal position, its outer end being slightly elevated, as shown in fig. 1; and when the two draw-heads are brought in contact with each other, the outer end of the link will enter the other draw-head, and catch over the hook B in said draw-head. In order to disconnect the two draw-heads, either lever E is raised or drawn upward, and the lower arm a will throw up the link C off from the hook B. In case of a car being thrown from the track, the draw-head of the car which falls or descends will disengage itself from the link C, as shown in fig. 2, the link in the elevated draw-head bearing against the outer end of the bottom plate thereof, which admits of the end of the link in the other draw-head passing off from the hook B in said draw-head.

I claim as new, and desire to secure by Letters Patent—

The fixed hooks B, in combination with the link-raisers D, connected to levers E, the springs F, and the link C, all arranged and applied to draw-heads A A, to operate in the manner, substantially as and for the purpose set forth.

C. C. CADY.
